INFANT'S RIDING TOY

Judson E. Cornish, 2237 Lake St., San Francisco, Calif.

Filed Mar 25, 1963, Ser. No. 74,121

Term of patent 14 years

(Cl. D34—15)

F i g. 1

F i g. 2

F i g. 3

F i g. 4

F i g. 5

FIGURE 1 is a top perspective view of an infant's riding toy showing my new design;

FIGURE 2 is a side elevational view of an infant's riding toy; the side opposite thereto being a mirror image thereof;

FIGURE 3 is a bottom plan view thereof;

FIGURE 4 is a front elevational view; and

FIGURE 5 is a rear elevational view thereof.

I claim:

The ornamental design for an infant's riding toy substantially as shown and described.
